UNITED STATES PATENT OFFICE.

WILLIAM H. SMALLEY AND EDGAR HATTON, OF HAVANA, ILLINOIS.

ASH-HANDLING APPARATUS.

933,129.

Specification of Letters Patent.

Patented Sept. 7, 1909.

Application filed January 28, 1909. Serial No. 474,775.

To all whom it may concern:

Be it known that we, WILLIAM H. SMALLEY and EDGAR HATTON, citizens of the United States, residing at Havana, in the county of Mason and State of Illinois, have invented or discovered certain new and useful Improvements in Ash-Handling Apparatus, of which the following is a specification, reference being had therein to the accompanying drawings.

Railroad round houses, or the approaches thereto, are generally provided between the tracks with pits into which ashes and cinders and sometimes the fires of the engines are dumped, and the accumulated ashes from these pits are usually subsequently shoveled into ash cars for removal. This requires considerable labor, and in handling the ashes and cinders they are sometimes spilled about so as to present an untidy appearance.

The present invention has for its object to provide convenient means for handling the ashes and cinders from ash pits of the kind above referred to without requiring the ashes and cinders to be shoveled out by hand. To this end the ash pits between the tracks are provided with rails for the support of receptacles for the ashes and cinders, and which receptacles preferably comprise cars or buckets loosely fitting in cages, and the latter are provided with wheels running on the tracks; so that the ash buckets or receptacles may be located in any desired positions beneath the engines to receive the ashes and cinders from the latter and which may be dropped from the engines directly into the said ash-buckets or receptacles. For coöperation with the buckets or receptacles there is provided a convenient hoisting device, by which said buckets or receptacles may be lifted from the cages in the ash pits and swung around over the ash cars on tracks conveniently near, and into which ash cars the cinders and ashes in the buckets or receptacles may be dumped.

To this end the buckets or receptacles are preferably provided at their bottoms with swinging dumping doors which are held in place by spring catches which latter may be released to permit the dumping doors or bottoms of the buckets to fall downward to dump the contents of the buckets into the ash cars.

In the accompanying drawings, Figure 1 is an elevation of an apparatus constructed in accordance with the present invention, and illustrative of the operation thereof.

Fig. 2 is an end view of the bucket-receiving cage in the ash pit. Fig. 3 is a detail view illustrative of the top portion of the swinging crane.

Referring to the drawings, 12 denotes an ash pit in which will be located suitably supported tracks 13 providing a tramway for the reception of wheels 14 of a cage 15 so that said cage may run freely on said tracks 65 to enable it to be located in any desired position beneath the engines. Adjacent to the tracks is located a crane preferably comprising a base or foot-block 16 of concrete (and which may be set into the ground if desired) and to which base or foot-block is preferably bolted a metal cap-plate 17 fitted for the reception of the lower end of an upright 18 which will preferably consist of a cast iron pipe of suitable size and length to 75 constitute the standard of a crane. The swinging portion or boom of the crane preferably consists of metal arms 19 brought together at their outer ends and attached at their inner ends by bolts 20 to a metal block 80 21 fitting the circular standard 18. The outer ends of the arms 19 are supported by inclined braces 22 the lower ends of which are attached by bolts 23 to a metal block 24, similar to the block 21, and through which 85 block 24 the circular standard 18 passes. The block 24 is held up by a collar 25 attached to the standard 18 by suitable set screw or set screws; and the upper block 21 is similarly held up on said standard by a 90 collar 26 either located directly beneath and in contact with said block 21, or in contact with an interposed swinging block or collar 27.

The bucket 28 is of suitable size to fit 95 loosely in the cage 15 and is preferably formed of a sheet metal body riveted to angle-iron corner bars and provided with central straps 29. At the bottom of the said bucket and supported by said straps 29 100 is a cross rod 30 on which are hinged doors 31 forming the bottom of the bucket, said doors being also preferably of sheet metal braced by hinge-straps 32 which run the full widths of the said doors. The bucket 105 is preferably considerably narrower at its bottom than at its top, and this construction enables the doors to be made narrower, and therefore stronger, than they otherwise would be. The hinge-straps are provided 110 at their outer ends with catches 33 adapted to coöperate with spring latches or catches

34 attached to the sides of the bucket or receptacle, and which spring latches or catches 34 may be released, when the contents of the bucket are to be dumped, by a bar or other 5 suitable device in the hands of the attendant.

The bucket or receptacle 28 is preferably provided at its ends with suitable hooks 35 for engagement with ropes or chains 36 for connection with a suitable hoisting device. 10 Said hoisting device preferably consists of a hook 37 supported at the end of a chain 38 running over the pulleys 39, said pulleys being attached to a shaft 40 the outer end of which is journaled in a yoke 41 supported 15 from the outer end of the crane arms 19 and the inner end of which shaft is journaled in the block 27 formed as a collar surrounding the standard 18, and which may, if desired, be an integral part of the block 21. 20 Near the inner end of the shaft 40 is a pulley 42 over which runs a hoisting chain 43 by which the hoisting device may be operated in a well-known manner by an attendant or workman. When the hoisting device 25 is operated to lift the filled bucket or receptacle 28 to a desired elevation the swinging portion or boom of the crane may be swung around to carry the bucket over an ash car on a suitably located track; and 30 when this has been done the contents of the bucket may be dumped into said ash car merely by disengaging the latches or catches 34 from the catches 33, thereby permitting the doors 32 to swing downward to release 35 the contents of the bucket. To prevent ashes or cinders from falling into the pit 12, outside of the bucket or receptacle, the edges of the pit are preferably provided with guards 44 of sheet metal or other suitable 40 material which will overhang the space between the bucket or receptacle and the side walls of the pit.

From the foregoing it will be understood that when the bucket or receptacle 28 has 45 been lowered into the cage 15 and disengaged from the lifting hook 37 the said cage, with the bucket or receptacle therein, may be moved on the tracks 13 to any desired location beneath an engine, and ashes and cinders may then be dumped from the engine directly into the bucket or receptacle. 50 When the latter becomes filled it may be run to a suitable position adjacent to the crane, and being engaged by the hoisting apparatus above described it may be lifted 55 to any desired height and then swung around over the ash car for dumping, the blocks 21 and 24, forming parts of the swinging portions of the crane, turning on the circular standard 18 in swinging the 60 bucket horizontally from one position to another. The crane will, in practice, preferably be steadied by guy ropes, as is common with cranes and derricks.

Having thus described our invention we 65 claim and desire to secure by Letters Patent:—

1. An ash handling apparatus comprising rails, forming a tramway, in an ash pit, a cage furnished with wheels fitted to run on 70 said rails, a dumping bucket adapted to be loosely received by said cage, and means for raising and lowering said bucket and for swinging it from over said pit to a dumping position aside from the pit. 75

2. An ash handling apparatus comprising an ash-pit provided near its top with rails, a cage provided near its top with wheels fitted to run on said rails, a dumping bucket adapted to be loosely received by said cage, 80 and means for raising and lowering said bucket and for swinging it from over said pit to a dumping position aside from the pit.

In testimony whereof we affix our signatures, in presence of two witnesses.

WILLIAM H. SMALLEY.
EDGAR HATTON.
